WORKMAN'S GARMENT

Paisley M. Sanderson, Georgetown, S. C.

Application May 17, 1934, Serial No. 726,138

1 Claim. (Cl. 2—227)

This invention relates to the broad class of wearing apparel and has more particular reference to garments of the so-called working man's type and more specific reference to the bib or apron portion of overalls, coveralls and the like.

As a general rule in making up a pair of overalls it is customary to embody therein what is called a bib. This is of course sometimes referred to as an apron as well as a vest. In any event, however, the apron portion of the garment is generally of one piece formation and attached to the upper waist band portion of the frontal part of the trousers of the garment. The free ends of the shoulder straps or suspenders are generally connected to the upper corner portions to hold the bib up in its regular shield forming position.

The novelty of the present invention is directed to the particular construction and formation of the apron or bib, this being made up of a pair of complemental independently and collectively usable sections buttoned or otherwise detachably connected together along adjacent edges, whereby to permit said sections to be spread open in warm weather or closed up in cold weather.

A second feature of novelty is predicated upon the sectional detachably jointed apron structure wherein the sections may be spread apart so that the shoulder straps can be slipped down over the shoulders to allow the trouser portion to be lowered for removal, making it unnecessary to detach the shoulder strap from the complemental portions of the apron.

Additional novelty is predicated upon this sectional apron structure wherein one section is provided with inner and outer accessory and convenience pockets, the pockets being contained within the marginal limits of said section and being arranged so as not to interfere with the comfortable fit of the garment.

Other features and advantages may become apparent from the following description and drawings:

In the drawings:

Figure 1 is an elevational view of a pair of overalls constructed in accordance with the present invention.

Figure 2 is a top plan view of the arrangement depicted in Figure 1.

Figure 3 is an edge elevational view of the duplex pocket equipped section of the bib or apron construction.

Figure 4 is an enlarged detail horizontal sectional view taken approximately on the plane of the line 4—4 looking downwardly in the direction 55 of the arrows.

The general assembly may well be seen in Figure 1 wherein it will be observed that the trousers portion of the overalls or garment is denoted by the numeral 5. This part of the structure is of conventional type, that is embodies the usual bifurcated legs equipped with pockets and frontal fly. It is also evident from Figure 2 that the back portion of the structure is of conventional form and includes regulation shoulder straps or suspenders 6. These are provided with adjusting slides or loops 7 shown in Figure 1 and the free end portions thereof are attached by adjusting buckles or equivalent devices 8 to the upper corner portion of the bib apron 9. Inasmuch as the expression bib and apron are used synonymously I will hereafter refer to the structure as an apron, it being thought that this is clearly comprehensive. With this in mind it will be observed that the apron, as a unit, is stitched or otherwise fastened to the waistband portion of the garment as indicated at 10 and is also separately fastened to buttons 11 carried by the back or seat portion of the garment. Thus far the structure is similar to the common or conventional overalls construction.

Considering in detail the preferred embodiments of the apron construction it will be observed that this is composed of a pair of complemental or companion panel-like sections or flaps 12 and 13. These are substantially identical in shape and proportion and cooperate together in forming a unitary apron. At the center and on its exterior section 12 is provided with an ordinary open top patch pocket 14. The adjacent or inner edges of the sections 12 and 13 overlap and are fastened together by buttons 15 or corresponding separable fastening means. This allows the two sections to be spread apart for cooling the chest or for allowing the shoulder straps to be slipped down off of the shoulders either separately or collectively to facilitate application and removal of the garment.

It will be noticed that the section 13 is provided with a duplex or double pocket assembly, that is to say it has an outside patch pocket 16 and an inside or interior pocket 17. These are of vertically elongated rectangular form and are fastened to said sections within the marginal limits thereof and the two pockets are in substantially superposed relationship, that is the inside pocket is directly behind or in alignment with the outside pocket. The two pockets together serve to reinforce this particular section 13 of the bib. In addition they add to the utility 55

thereof in that they may be employed as receptacles for convenience and for holding various articles. It will be noticed for example that the entire pocket 17 is stitched around three of its edges and that its mouth portion 18 is open at a point adjacent the overlapping or separably buttoned edge portions of the two overlapping sections 12 and 13. This makes it handy to slip articles into the pockets 17 by simply unbuttoning the sections 12 and 13. On the other hand it will be observed that the pocket 16 is of slightly different formation, that is to say it is stitched around the edges as at 19, 20, 21 and 22. In other words it is stitched around four of its edges with the inner edge portion left open to provide a restricted entrance or mouth at 23. Both of the mouths 23 and 18 are in longitudinal registry and alinement with the slot defined by the buttoned overlapping edges of the sections 12 and 13. Obviously the pocket 16 is of the safety type and is useful for carrying a chained watch or the like.

It is thought that persons skilled in the art to which the invention relates will be able to obtain a clear understanding of the invention after considering the description in connection with the

drawings. Therefore, a more lengthy description is regarded as unnecessary.

Minor changes in shape, size, and rearrangement of details coming within the field of invention claimed may be resorted to in actual practice, if desired.

Having thus described my invention, what I claim as new is:

A pair of overalls including a trousers portion and a frontal apron portion, together with shoulder straps connected with the trousers portion and upper corners of the apron, said apron being longitudinally slit to define a pair of companion sections, the split portion thereof having the adjacent edges disposed in overlapping relation and secured by separable fasteners, one of said sections being provided on its exterior with a patch pocket and on its interior with a similar patch pocket, both of said patch pockets being of vertically elongated rectangular design and mounted within the marginal limits of said apron section, and both of said pockets having their entrance or mouth portion disposed in parallelism with and adjacent the separable or overlapping edge portions.

PAISLEY M. SANDERSON.
